UNITED STATES PATENT OFFICE

LEO SILBERSTROM, OF BERLIN, GERMANY

DUPLICATING

No Drawing. Application filed June 5, 1926, Serial No. 114,020, and in Germany February 27, 1926.

In the preparation of originals for duplicating processes involving the use of plain plates which are made neutral or acid (such as the so-called "Opalograph" process), alkaline inks, or colouring or inking ribbons or pads containing an alkaline preparation, are used. It has already been suggested in such processes to prepare the original by means of an ammoniacal ink, or to add to the ink a fixed alkali, or a carbonate thereof or a salt having an alkaline reaction. Ammoniacal inks are unsatisfactory on account of the volatility of the ammonia. Inks containing a fixed alkali or an alkaline salt react only very slowly with the preparation on the plate, whilst if the sensitivity of the plate is enhanced, for instance, by the addition of a sulpho-cyano compound, there is the danger that the white portions will become tinted on account of the high sensitivity.

By the present invention, the original to be duplicated is prepared by means of an ink or colour containing hexamethylene-tetramine. Satisfactory results are thereby obtained inasmuch as on the one hand, the reaction between the ink of the original and the preparation on the plate is exceedingly sensitive, whilst on the other hand, the stability of the ink or writing in the original is practically unlimited on account of the non-volatility of hexamethylene-tetramine. Instead of hexamethylene-tetramine, a salt thereof may be used.

In particular, the invention permits the production of a satisfactory inking or colouring ribbon or pad for use in connection with duplicating processes, a problem which has hitherto not been solved in a manner free from objection. If, for example, hexamethylene-tetramine is added to one of the usual preparations for impregnating the ribbon or pad, for instance in a proportion amounting to 50 per cent of the preparation, the typescript produced with the aid of the impregnated ribbon reacts with sufficient rapidity and clearness with the preparation on the plate, without any treatment being necessary to increase the sensitivity of the latter.

The process may also be carried out by preparing the original by means of a viscous or

adhesive ink, or by producing typescript with the aid of a ribbon or pad containing a viscous or adhesive substance, and then dusting over the original so prepared a powder consisting of or containing hexamethylene-tetramine or a salt thereof. 55

The term "hexamethylene tetramine" occurring in the following claims is used in the sense of including hexamethylene-tetramine itself as well as its salts. 60

Having thus described the nature of the invention and the best means I know of carrying the same into practical effect, I claim:—

1. In a duplicating process of the kind described herein, the step for forming the characters of the original with a material containing hexamethylene-tetramine. 65

2. In a duplicating process of the kind described herein, the step which comprises forming the original with an ink containing hexamethylene-tetramine. 70

3. In a duplicating process of the kind described herein, the step which comprises adding hexamethylene-tetramine to the ink 75 from which the original is prepared.

4. An ink, for the process referred to in claim 2, containing hexamethylene-tetramine.

5. An inking ribbon or pad, for the process referred to in claim 1, impregnated with hexamethylene-tetramine. 80

In testimony whereof I have signed my name to this specification.

DR. LEO SILBERSTROM. 85
